UNITED STATES PATENT OFFICE

SIDNEY J. V. BOVEY, OF CHICAGO, ILLINOIS, ASSIGNOR, BY MESNE ASSIGNMENTS, TO
METALCRAFT HEATER CORPORATION, OF GRAND RAPIDS, MICHIGAN, A CORPORA-
TION OF MICHIGAN

AIR-CIRCULATING DEVICE FOR VEHICLES, HEATERS, AND THE LIKE

Application filed September 13, 1926. Serial No. 134,984.

This invention relates to an air circulating device which is particularly adapted for use in connection with circulating air to heaters or ventilating vehicle bodies and the like.

necessary amount of air because the air is not properly forced through the funnel by reason of its shape and its position with respect to the fan blade. In the present invention I have provided an air circulating device which comprises a hood of a special form which is so positioned with respect to the rotating blades of the fan so that the required amount of air can be supplied under pressure to the vehicle heater and at the same time the amount of space occupied by the device is reduced to a minimum.

5 One of the objects of the present invention is to provide an improved form and simplified construction of an air circulating device.

In illustrating one form of my invention I have shown the same in connection with the conventional form of internal combustion engine 10 which is provided with the usual engine head 11 and securing bolts 12. 65

Another object of the invention is to provide a simple and compact air circulating device which will occupy a minimum amount of space and at the same time will furnish a relatively large amount of air to the vehicle heater when used in connection with a heater or furnish a relatively large amount of air when used in connection with a ventilating device for vehicle bodies.

usual engine head 11 and securing bolts 12. The engine 10 is provided with the usual

20 A still further object of the invention is to provide a novel and improved construction of air circulating device which is adapted to operate in conjunction with the radiator fan of an internal combustion engine for supplying and circulating air to a vehicle heater and the like.

revolving radiator fan 13 which in turn is provided with fan blades 14. The engine 10

25 These and other objects are accomplished by providing the construction and arrangement of the various parts in the manner hereinafter described and particularly pointed out in the appended claims.

is also provided with the usual exhaust manifold 15. The air circulating device which is

Referring to the drawings:

30 Fig. 1 is a fragmentary top plan view of the conventional form of internal combustion engine showing my improved air circulating device embodied therein,

is preferably made of sheet metal and is rectangular in cross section so as to occupy a

with relatively narrow sides 19 and 20 and flat top and bottom portions 21 and 22 respectively. The side 19 is formed by a vertical

In air circulating devices heretofore used of the type in which the engine fan is employed for supplying or circulating of air to the vehicle heater, considerable difficulty has

tively. The side 19 of the conduit or casing 18 is enlarged as shown at 23 with the lower

46 been experienced in furnishing the proper supply of air to the heater without the necessity of providing a relatively large and cumbersome device adjacent the engine fan and

edge thereof inclined downwardly on a straight line as shown at 24 and the outer edge thereof extending vertically upward as

50 engine. The funnel type of device now generally in use does not efficiently supply the

edge thereof extending vertically upward as shown at 25. The upper edge of the enlarged portion 22 is curved downwardly as shown at

portion 23 is curved downwardly as shown at 26. The other side 20 of the conduit or casting 18 is similarly enlarged as shown at 27.

ing 18 is similarly enlarged as shown at 21, but has the flat surface thereof inclined inwardly toward the axis of the fan 13 so that

wardly toward the walls of the fan 12 so that the mouth of the casing extends substantially across the shorter edge of the fan blade 14 as

clearly shown in Fig. 1.

From this construction it will readily be ¹⁰⁰

seen that as the fan blade 14 is passing the mouth of the conduit or casing 18 it gathers in substantially the entire amount of the air discharged rearwardly of the fan blade and by reason of the downwardly curved portion of the top portion 21 of the casing. With this construction the air is forced under pressure through the conduit in such a manner that a maximum amount of air is circulated through the casing with a minimum amount of space being occupied by the casing proper. The forward end of the casing is positioned in close proximity with the rear edge of the revolving fan blades so that the fan blades when passing the mouth of the casing 18 will assume an angle with respect to the vertical edges 25 of the enlarged portions 23 and 27 of about 60°, as is clearly shown in Fig. 2. The rear end of the conduit or casing 18 is connected by a suitable conduit 28 to the vehicle heater, ventilating device, or other similar devices.

The bottom 22 of the casing extends downwardly along the inclined edges 24 of the enlarged portions 23 and 27 as shown at 29 and stops short of the vertical edges 25 so as to form an opening 29 on the lower side thereof adjacent the mouth through which air may be drawn by reason of the action of the fan blades.

From the description it will be readily seen that by providing a conduit or casing in which the mouth thereof is positioned so as to extend substantially across the fan blades and with the upper surface of the mouth extending downwardly, a maximum amount of air will be forced under pressure through the conduit or casing and at the same time, by reason of my improved construction a minimum amount of space will be utilized.

While in the above specification I have described one embodiment which my invention may assume in practice it will of course be understood that the same is capable of modification and that modification may be made without departing from the spirit or scope of my invention as expressed in the following claims.

What I claim as my invention and desire to secure by Letters Patent is:

1. An air circulating device for vehicle heaters and the like comprising an open ended conduit having a relatively large mouth lying parallel and co-extensive with the blades of the fan as they assume a horizontal position.

2. An air circulating device for vehicle heaters and the like comprising an open ended conduit having an enlarged downwardly extending mouth extending radially with respect to the center of the fan.

3. An air circulating device for vehicle heaters and the like in combination with an engine fan having fan blades thereon, comprising a conduit having a downwardly extending enlarged mouth positioned with re-

spect to said fan blades so as to extend substantially across the length of the blades as said blades revolve past said mouth.

4. An air circulating device for vehicle heaters and the like in combination with an engine fan having blades thereon, comprising a conduit having a downwardly extending mouth secured adjacent said fan, said mouth being substantially coextensive with the length of said fan blades as they pass said mouth.

5. An air circulating device for vehicle heaters and the like in combination with an engine fan having fan blades thereon, comprising a open ended conduit having an enlarged end adjacent said fan, said enlarged end having a downwardly curved top and positioned substantially parallel with the blades of the fan when they assume a horizontal position whereby as said fan blades pass said end the air is forced through said conduit.

6. An air circulating device for vehicle heaters and the like in combination with an engine having a fan, comprising a casing secured to said engine having a free open end thereof positioned at substantially the same horizontal level as the axial center of said fan, the sides of said casing adjacent said fan positioned at different angles with respect to said casing whereby said fan forces the air under pressure through said casing.

7. An air circulating device for vehicle heaters and the like in combination with an engine having a fan, comprising a conduit secured to said engine having an open end positioned adjacent said fan, said conduit having a portion extending inwardly and a portion extending downwardly with respect to said fan, said downwardly extending portion located on a radial line with respect to said fan for forcing the air through said conduit under pressure.

8. An air circulating device for vehicle heaters in combination with an engine having a fan journaled thereon, comprising a casing secured to said engine and having an enlarged uncovered portion formed on the forward end thereof adjacent said fan, said enlarged portion having an inclined wall extending inwardly toward the pivot of said fan, and an upper wall curved downwardly with respect to said fan and having its forward edge extending horizontally and radially with respect to said fan whereby as said fan passes the mouth of said casing substantially the entire amount of air that is charged from said fan is forced through said casing.

9. An air circulating device for vehicle heaters and the like in combination with an engine fan having blades thereon, comprising an open ended conduit having an enlarged mouth adjacent said fan, said mouth having an inwardly extending side and a downwardly extending top whereby substantially the

entire amount of air discharged rearwardly of the fan blades as they assume a horizontal position parallel to the mouth of said conduit will be gathered into the mouth of said conduit.

5 In testimony whereof I have signed my name to this specification, on this 31st day of August, A. D. 1926.

SIDNEY J. V. BOVEY.
